VEHICLE ANTENNA

Daniel J. Gaida, Hayward Park,
St. Cloud, Minn. 56301

Filed Apr. 18, 1966, Ser. No. 1,920

Term of patent 14 years

(Cl. D14—6)

FIGURE 1 is an elevation of a vehicle antenna showing my new design.

FIGURE 2 is a more detailed illustration of the base element of my new design.

FIGURE 3 is a top view of my new design.

I claim:

The ornamental design for a vehicle antenna, substantially as shown and described.
